UNITED STATES PATENT OFFICE.

OSCAR F. MANN, OF INDIANAPOLIS, INDIANA, ASSIGNOR TO NINA C. MANN, OF INDIANAPOLIS, INDIANA.

SCAFFOLD.

Application filed April 30, 1924. Serial No. 709,969.

To all whom it may concern:

Be it known that I, OSCAR F. MANN, a citizen of the United States, residing at Indianapolis, in the county of Marion and State of Indiana, have invented new and useful Improvements in Scaffolds, of which the following is a specification.

This invention relates to scaffolds such as are required by masons, carpenters, and 10 the like in building construction and repairs, and the object is to provide a scaffold that can be quickly erected, and rapidly raised without rebuilding as the work progresses.

The custom heretofore has been to utilize 15 lumber ordered for the building under erection, with which to make the uprights, braces and platforms, and to unite the pieces by nailing them together, with the result that the lumber is full of nails, and much of it 20 so split and damaged as not to be available for the purpose originally intended when taken down.

Another object of my invention is to utilize less lumber, and that without nailing it, 25 or subjecting it to danger of damage by use in the scaffold.

A further object is to provide a safe and inexpensive scaffold.

I accomplish all of the above, as well as 30 other minor objects which will hereinafter appear, by the mechanism illustrated in the accompanying drawing, in which—

Fig. 1 is a side elevation of a scaffold embodying my invention, same being shown 35 beside a brick wall under construction. Fig. 2 is an end elevation of the same. Fig. 3 is a section on the line 3—3 of Figs. 1 and 2, showing the scaffold platforms and supports in top plan view, Fig. 4 is a cross-section of the upper platform on the line 4—4 of Fig. 3, and Fig. 5 is a cross-section on the line 5—5 of Fig. 2.

Like characters of reference indicate like parts in the several views of the drawing.

40 A workingman's platform 6, is made out of two two-by-eight inch planks which rest upon metal angle-bars 7, 7, arranged in pairs and united by bolts 9, which pass through the bars and also through spacers 50 10, between each.

The spacers 10 as here used are made out of channel-iron, the perforated parallel flanges of which bear against the bars 7, 7, as shown in Fig. 5. The pair of bars 7, 7, 55 receive triple two-by-four inch vertical

timbers 11, between them, with a sliding fit. Movement of the vertical timbers in the directions of their narrowest dimensions is prevented by spacers 10 and bolts 9 against one edge of each, and by bolts 12 against the 60 other edge.

Each timber 11, is provided with a longitudinal series of holes 13, in which pins 14 are inserted to retain a given vertical position of the bars 7, 7, on the timbers 11. 65

The lower ends of the triple timbers 11, rest upon a wide plank 15, to distribute the load on soft ground, and the tops of the triple timbers are preferably joined by a pair of separated two-by-four timbers 16 and 17, 70 and by a pair of diagonal braces 18 and 19, bolted to the members 11, in the manner best shown in Fig. 2. The lower timber 17 preferably projects outwardly to support a metal clip 20, in which a pulley-block (not 75 shown) may be engaged to hoist building material to a platform 21, said platform being elevated above that on which the workman stands.

Only the two outermost ones of each set 80 of triple uprights 11, are utilized for supporting the platform 21. These are held between a pair of angle-bars 22, 22, united by bolts 9 and 12, and separated by spacers 10, as described for the bars 7. The bars 22 85 are connected with the bars 7 by a pair of diagonal brace-bars 23.

Supported upon the bars 22 are the angle-bars 24, 24, with a horizontal flange of each contacting with the bars 22 and with the 90 other flange of each contacting respective adjacent uprights 11. The bars 24 extend for approximately a yard on each side of the bars 22, and their outer ends are connected with the angle bars 7 by the diagonal T-bar 95 braces 25, 25.

The top platform 21 usually comprises two two-by-eight inch planks 26 and 27, each laid in and against the inner angles of the respective bars 24, and by outside two-by-four 100 pieces 28, 28, that only extend to, but do not pass the uprights 11. Metal straps 29 are laid across the top of the platform thus made up, and the straps are bolted to an angle-bar below where there is such, or to another 105 similar strap 30, placed transversely of and under the platform.

Where the platform timbers are not long enough to reach from one set of uprights 11, to the next, I join them anywhere by insert- 110

ing the body-flange of an inverted T-bar 31 between the timbers to be joined and extending a suitable distance for strength on each side of the joint, and clamp the ends of the bars 31 between a pair of cross-straps 29 and 30, as shown.

The angle-bar pairs 7, 22 and 24, bolted together and braced as above described, form a unit that can be carried easily and 10 placed by one man. These will be used every 16 or 18 feet apart around a building under construction, to make a scaffold going entirely around the building if so desired, or extending only part way around at a time, and 15 moved further as required.

By placing clips 20 between the two outer uprights 11, on timbers 17, along the whole length of the scaffold, and connecting the clips by block-and-tackle with the metal unit 20 below, the entire scaffold may be lifted to keep pace with the laying of the wall of the building, and the raised positions of the scaffold will be retained by appropriately changing the pins 14 to upper holes 13. The 25 scaffold may be lowered by a reverse operation.

The uprights 11, will generally be retained for scaffold use, but the platform-boards which have not been cut, or driven into with 30 nails, are as good as new for use in the construction of the building, and will usually be so used.

What I claim as new is—

1. A scaffold comprising a platform, a 35 pair of horizontal bars extending transversely of and under the platform and supporting it, spacers between the pair of bars, bolts rigidly uniting the pair of bars, a second like pair of horizontal bars above the first 40 pair, diagonal braces connecting the two pairs, a pair of bars crossing and supported on the second pair, diagonal braces from the ends of the cross bars to the first pair of horizontal bars, a second platform on the 45 second pair of bars and the cross bars, a plu-

rality of vertical supporting members slid- 50 ingly assembled between the spaced apart bars of both horizontal pairs of bars, upon which the horizontal pairs are vertically adjustable, and means for obtaining a given adjustment of the horizontal pairs on the vertical members.

2. A scaffold comprising triple vertical supporting members, a pair of horizontal angle bars slidingly receiving all of the vertical supporting members between them, a second shorter pair of horizontal angle bars above the first pair slidingly receiving the two outermost of the triple supporting members between them, spacers holding both 60 pairs of horizontal bars apart and bolts holding them together, said spacers and bolts also preventing lateral displacement of the vertical members in the directions of the lengths of the pairs, diagonal braces between 65 the upper and lower pairs of angle bars, a third pair of angle bars upon and at right angles with the second pair, diagonal braces extending from the ends of the third pair of bars to the first pair of bars, a platform on 70 the second and third pairs of bars and a second platform on the first pair of bars spaced laterally with respect to the first platform.

3. In a platform joint for scaffold plat- 75 forms, the combination with a plurality of timbers comprising the width of the plat- 80 form, some of said timbers being transver- sely divided with abutting ends, of inverted T-bars extending an appreciable distance on each side of said transverse divisions with 85 the stem-flange of the T-bar between adja- cent timbers, a cross-bar under each end of the T-bars, a cross bar upon the platform over each of said under cross bars and bolts connecting each pair of upper and lower 85 cross bars together to form clamps.

Signed at Indianapolis, Indiana, this the 28th day of April 1924.

OSCAR F. MANN.
